UNITED STATES PATENT OFFICE.

ERNEST LESLIE RANSOME, OF CHICAGO, ILLINOIS.

LINING TUNNELS.

SPECIFICATION forming part of Letters Patent No. 545,978, dated September 10, 1895.

Application filed March 18, 1895. Serial No. 542,247. (No model.)

To all whom it may concern:

Be it known that I, ERNEST LESLIE RANSOME, a citizen of the United States, residing at Chicago, in the county of Cook and State 5 of Illinois, have invented a new and useful Improvement in Lining Tunnels, of which the following is a specification.

My invention particularly relates to lining tunnels with concrete, and has for its object 10 the closer juxtaposition of the concrete to the upper surface of the tunnel. The usual way of lining tunnels with concrete is to set up false work or molds within the tunnel and to fill in the space between the tunnel-surface 15 and the false work with concrete. In practice it has been found extremely difficult, if not impossible, with ordinary false work to so build the crown of the lining that it will remain solid and tight up against the excavated or other surface of the tunnel. In 20 packing concrete about the bottom or sides of the tunnel no such difficulty exists, because the concrete by its own weight assists the packing and tends to force itself close to 25 the adjacent surfaces; but at the crown of the tunnel the concrete cannot be fed from above. It has to be forced into position horizontally, and by its own weight it settles down and away from the crown of the tunnel. I overcome this difficulty by my present invention, which consists in first placing 30 the concrete and then forcing it hard up against the surface of the tunnel by expanding the false work so as to contract the space 35 occupied by the concrete. This expansion is made before the concrete sets, but after the work of filling in the lining has so far progressed ahead as to insure that the concrete compressed by the expansion of the mold 40 will not be further disturbed to any detrimental extent by the continued progress of the work.

The accompanying drawings illustrate how this process may be carried out. 45 Figure 1 is a longitudinal section of a part of a tunnel in the process of being lined with concrete. Figs. 2 and 3 are sections on lines X X and Y Y, respectively, of Fig. 1. Fig. 4 is an end elevation of a traveling core-mold 50 having a sloping working face. Figs. 5 and 6 are sections similar to Figs. 2 and 3, showing a modified construction.

In Figs. 2 and 3 the expansion is made by a sliding block E, which is suspended by bars F and pins F' at the required level, as shown in Fig. 3, until the sectional core is in place and the work has sufficiently progressed, when the block is thrust upward, by a jack or other means, until it has expanded the mold and compressed the concrete sufficiently. Then 60 it is held in that position by inserting pins F' through the lower holes of bars F, as shown in Fig. 2. By beveling this block, as shown, the perimeter of the mold can be extended at the same time that the crown is being raised. 65

In Figs. 5 and 6, instead of using a sliding block the contraction and expansion are made by the movement of shutter-like pieces G G. These pieces partly rest upon the frame work of the core-mold at H and partly upon the elevating-screw I. This screw is supported by the bar K, which is carried by the lugs L. The expansion-pieces are raised to the required height by means of the screw I and are held in place by one or more bars M, bolted 70 to the lugs N, as shown, wedges O being inserted between the shutters and the bar for keying up tightly. The tunnel being excavated to the line A, a traveling core-mold B is placed in position and is surrounded 75 with concrete P while being drawn along in the well-known manner. In the rear of this traveling mold sectional cores B are placed, one ahead of another, as fast as room is made for them by the forward movement of the 80 traveling mold. As this traveling mold draws away from the sectional cores, the concrete settles down upon them. This settlement increases the unfilled space at C. After the traveling mold has so far progressed ahead that 85 the jarring occasioned by the placing of the concrete is no longer felt, then the sectional molds are expanded at X X until they are brought to their proper height and the concrete above them has been compressed until 90 it entirely and tightly fills the space C and the excess thereof flows ahead. These sectional core-molds then remain in place until the concrete has sufficiently set, when they are removed. 95

I do not limit this invention to sectional cores, neither in conjunction with nor independent of a traveling mold. It can be applied equally well to any ordinary false work. 100

Nor do I limit this invention to concrete alone. It is equally applicable to any like plastic material.

Having thus described my invention, what 5 I claim is—

1. The method of lining tunnels with concrete which consists in introducing the concrete between the mold and the wall of the tunnel and in compacting the same against 10 the wall by pressure from within the mold.

2. The method of lining tunnels with concrete which consists in introducing the concrete between the mold and the wall of the tunnel and in forcing the concrete into contact with the upper portion of said wall by 15 an upward pressure from within the mold.

ERNEST LESLIE RANSOME.
